(57) **CLAIM**

The ornamental design for an electronic cigarette assembly, as shown and described.

DESCRIPTION

FIG. 1 is an enlarged perspective view of an atomizer according to a first embodiment shown as a component 1 removed from the assembly in FIGS. 15-21 for clarity of disclosure;

FIG. 2 is an enlarged front elevational view thereof; FIG. 3 is an enlarged rear elevational view thereof; FIG. 4 is an enlarged left side elevational view thereof; FIG. 5 is an enlarged right side elevational view thereof; FIG. 6 is an enlarged top plan view thereof; FIG. 7 is an enlarged bottom plan view thereof; FIG. 8 is a perspective view of a power supply shown as a component 2 removed from the assembly in FIGS. 15-21 for clarity of disclosure; FIG. 9 is a front elevational view thereof; FIG. 10 is a rear elevational view thereof; FIG. 11 is a left side elevational view thereof; FIG. 12 is a right side elevational view thereof; FIG. 13 is an enlarged top plan view thereof; FIG. 14 is an enlarged bottom plan view thereof; FIG. 15 is a perspective view of an electronic cigarette assembly where component 1 and component 2 are shown in an assembled state of use; FIG. 16 is a front elevational view thereof; FIG. 17 is a rear elevational view thereof; FIG. 18 is a left side elevational view thereof; FIG. 19 is a right side elevational view thereof; FIG. 20 is an enlarged top plan view thereof; FIG. 21 is an enlarged bottom plan view thereof; FIG. 22 is an enlarged perspective view of an atomizer according to a second embodiment shown as a component 1 removed from the assembly in FIGS. 36-42 for clarity of disclosure; FIG. 23 is an enlarged front elevational view thereof; FIG. 24 is an enlarged rear elevational view thereof; FIG. 25 is an enlarged left side elevational view thereof; FIG. 26 is an enlarged right side elevational view thereof; FIG. 27 is an enlarged top plan view thereof; FIG. 28 is an enlarged bottom plan view thereof; FIG. 29 is a perspective view of the power supply shown as component 2 removed from the assembly in FIGS. 36-42 for clarity of disclosure; FIG. 30 is a front elevational view thereof; FIG. 31 is a rear elevational view thereof; FIG. 32 is a left side elevational view thereof; FIG. 33 is a right side elevational view thereof; FIG. 34 is an enlarged top plan view thereof; FIG. 35 is an enlarged bottom plan view thereof; (Continued)

FIG. 36 is a perspective view of combined electronic cigarette assembly where component 1 and component 2 are shown in an assembled state of use;
FIG. 37 is a front elevational view thereof;
FIG. 38 is a rear elevational view thereof;
FIG. 39 is a left side elevational view thereof;
FIG. 40 is a right side elevational view thereof;
FIG. 41 is an enlarged top plan view thereof; and,
FIG. 42 is an enlarged bottom plan view thereof.

The dash-dot-dash broken lines represent boundaries of the claimed design; the dash-dot-dash broken lines themselves form no part of the claimed design, and the portion within the dot-dash broken lines forms no part of the claimed design.

The dash-dash lines in the drawings depict portions of the electronic cigarette assembly that form no part of the claimed design.
